his attorney.

UNITED STATES PATENT OFFICE.

HENRY A. GOEBLER, OF CONNERSVILLE, INDIANA, ASSIGNOR OF ONE-HALF
TO WILLIAM F. THOMAS, OF RICHMOND, INDIANA.

ADVERTISING DEVICE.

SPECIFICATION forming part of Letters Patent No. 620,868, dated March 7, 1899.

Application filed March 12, 1896. Serial No. 582,987. (No model.)

To all whom it may concern:

Be it known that I, HENRY A. GOEBLER, a citizen of the United States, residing at Connerville, in the county of Fayette and State 5 of Indiana, have invented certain new and useful Improvements in Optical Illusions and Advertising Devices, of which the following is a specification.

My invention relates to improvements in advertising devices, or, more especially speaking, to an apparatus for producing an optical illusion, the object of which is for use mainly in symbolically advertising the goods or wares of various manufacturers, tradesmen, or dealers; and the invention consists in the novel features of construction hereinafter fully described, and particularly pointed out in the claims.

In the accompanying drawings, Figure 1 is 20 a front elevation of a single plane glass mirror or unbroken highly-reflecting surface, showing my improvement in perspective as it appears in use, the same being in this instance a half keg or barrel of any suitable 25 size attached to the face of said mirror. Fig. 2 is a vertical section of said mirror, taken on a line with the left-hand edge of the half-barrel attached thereto and shown in elevation. Fig. 3 is a central vertical section of the device as shown in Fig. 1, looking from left to 30 right. Fig. 4 is a rear elevation of the half-keg or fragmentary object shown in the preceding views, showing a sucker-pad mechanism for attaching the same in place directly 35 to the mirror-face. Fig. 5 is a view similar to Fig. 4, but with said sucker-pad mechanism omitted; and Fig. 6 is a sectional elevation showing a screw-joint device for detachably securing the half-keg or fragmentary object to the sucker-pad frame.

In the views, A represents a single plane glass mirror or other highly - polished unbroken reflecting-surface, and B is a fragmentary object, herein shown as a symmetrical 45 fragment or portion of a keg or barrel whose butt-end is attached directly to the face of said mirror or reflecting-surface A in any suitable manner.

In Figs. 3 and 4 I show mounted within the 50 back end of the fragmentary object B, which

end is formed with a hollow or cavity, one form of attaching device formed of a spider or skeleton frame C, having one or more sucker or air-exhaust pads c mounted thereon. c' represents a manipulating handle or stem 55 projecting from each of the sucker-pads c into said hollow or cavity. The fragmentary object B is herein represented as in the form of a half keg or barrel, being preferably constructed of thin light material suitably 60 striped or lined in imitation of the usual longitudinal staves and bound with hoops b.

The head b' of the half keg or barrel B is preferably hinged, as shown at a, so as to permit it to be opened to afford ready access to 65 the attaching devices arranged in the hollow or cavity of the object B, and said head is provided with a spring-catch a', serving to hold it in closed position. The head b' thus serves as a door to close the front end of said 70 hollow or cavity.

The flaring rim b² of the barrel-head forms the outer or end hoop, as it overlaps the outer end of the body of the barrel, and an auxiliary sign D is supported thereby, its lower ends 75 or feet d being inserted under said rim b² at any desired part thereof. The front face of the head b' is provided with a clock-dial E, and surrounding the latter is placed any desired advertising matter. To render the device 80 useful, I mount a clock mechanism E' on the back of the head b', and the hands of said mechanism operate on the dial to show the time.

In operation I moisten the soft-rubber pads 85 c and then swing the head b' open, so that each pad can be tightly pressed against the reflecting-surface from inside the figure B, the frame C being made somewhat flexible, so as to permit the movement of the pad-stems 90 back and forth. The stems are then manipulated so as to draw the central portions of the pads away from the reflecting-surface, leaving the pads adhering thereto by the atmospheric pressure, after which the head b' is 95 closed and secured by means of its spring-catch. The reflection or image I of the fragmentary object B in the reflecting-surface or mirror is such that a complete figure, herein represented as a barrel or keg, is caused to 100

appear to view, as best seen in Fig. 1. The reverse lettering of the words "For sale here" or other matter on the back of the sign D is made to appear in the mirror in corrected form. In this way is produced the illusion of a complete barrel or other object suspended in the air or passed through a hole in a clear glass. The clock is designed to attract the attention of the observer, and thus forms an important adjunct on the device, although it may of course be dispensed with, if desired.

As shown in Fig. 5, the sucker-pads for attaching the object B to the mirror are dispensed with, the flange B' being provided with a coat of paste or cement for this purpose. In a similar manner in some cases cement may be applied to the sucker-pads for causing them to adhere more securely and permanently to the mirror.

In Fig. 6 is shown a construction wherein the body portion of the object B is detachably connected to the frame which carries the sucker-pads. A screw-joint is interposed between them, being formed of a male screw F, carried on the inner face of the spider or frame C, and a screw-threaded socket or cap G, mounted within a spider or skeleton frame G', free to revolve therein. The socket or cap G is provided with a handle or head, so that it may be conveniently rotated within the spider or frame G', so as to screw the two parts together. The spider G' is secured to the object B inside the hollow or cavity of the same, and when it is desired to attach or detach the fragmentary object the door or head b' is swung open and the cap or socket G turned by means of its head or handle, so as to unscrew it from or screw it upon the screw F. In this way the fragmentary object B may be conveniently removed, so that the mirror may be cleaned without necessitating the removal of the spider or frame C or the attaching devices carried thereby from the mirror.

It is obvious that any other object B than a half barrel or keg may be employed—such, for instance, as a fragmentary portion of a shoe, hat, or the like—preferably representative, of course, of the business to be advertised. It is essential, however, in order to secure the best results, that the mirror or reflecting-surface be in the form of a plane and unbroken surface and that the object attached to the face thereof be a symmetrical half of the object to be represented, this half being reproduced by its reflection in the mirror, so as to complete the object which it is desired to represent. It is also necessary in order to secure the best results that the object B be secured to the mirror with its axis per-

pendicular to the plane surface thereof, and said object should be secured at the central part of the mirror, so that the reflecting-surface shall extend on each side thereof, so as to complete the representation of the object no matter on which side of the device the observer stands. Also by forming the object B with a hollow or cavity to receive and house the means used for attaching the object to the mirror it will be seen that a material advantage is gained, since it is permitted to entirely conceal the attaching means and to form a perfect joint between the plane surface of the mirror and the rear edges of the object B.

Having thus described my invention, what I claim, and desire to secure by Letters Patent, is—

1. In an advertising device, the combination of a polished, unbroken, plane, reflecting-surface or mirror, a symmetrical fragment of an object to be represented by the device, and means housed within said fragment for attaching the same to the reflecting-surface so that it will be reproduced by reflection to complete the object to be represented, and a door carried by the fragment to afford access to said attaching means, substantially as set forth.

2. In an advertising device, the combination of a plane, polished, unbroken reflecting-surface or mirror, a symmetrical fragment of an object to be represented by the device, said fragment having a hollow or cavity formed in it and having in its front part a hinged door adapted to afford access to said hollow or cavity, and means arranged in the hollow or cavity of said fragment for attaching the fragment to the reflecting-surface in position to be reproduced by reflection to complete the object to be represented, substantially as set forth.

3. In an advertising device, the combination of a mirror or other highly-polished reflecting-surface, a fragmentary portion of an object to be represented by the device, a hinged front door or head for said fragmentary portion, a sucker-pad mechanism mounted independently within said fragmentary portion and having a screw-threaded projection thereon, a screw-threaded socket freely mounted in a frame within said fragmentary portion, and a timepiece carried by said hinged door, substantially as set forth.

In testimony of which invention I have hereunto set my hand.

HENRY A. GOEBLER.
